UNITED STATES PATENT OFFICE.

ERASTUS EDWIN WINKLEY, OF LYNN, AND HERMAN AUGUSTUS DAVENPORT, OF BROCKTON, MASSACHUSETTS, ASSIGNEES TO UNITED SHOE MACHINERY CORPORATION, OF PATERSON, NEW JERSEY, A CORPORATION OF NEW JERSEY,

LEVELING MACHINE.

Application filed May 31, 1923. Serial No. 642,678.

This invention relates to machines for pressing shoes and is disclosed in its application to a leveling machine of the so-called automatic type in which a leveling tool and a shoe carrying jack are automatically relatively reciprocated to cause the tool to operate over the shoe bottom in various paths.

In machines of the above-mentioned type, as usually constructed, the jack is moved from a shoe-receiving position to carry the shoe, toe end foremost, under the leveling roll, and after such reciprocatory movements as are necessary in the operation of the roll on the shoe, returns to starting position to carry the shoe out from under the roll. As the toe end of the shoe is carried under the roll it is necessary to guard against forcible impact of the roll on the end of the shoe, such for example as to bend the edge of the sole unduly and thereby damage the shoe; and to avoid similar damage it is necessary to prevent the roll from falling abruptly from the toe as the shoe is carried out from under the roll. To avoid such damage to the shoe, it is a common practice to jack the shoe so low that its toe end passes under the roll, and out from under it, without any very substantial pressure of the roll on the sole. As an alternative, machines are sometimes provided with a roll-receiver on the jack in front of the toe to guide the roll up substantially to the level of the toe end of the sole before it engages the shoe.

Either of the above-mentioned expedients, having in view the prevention of damage to the toe end of the shoe, is open to serious objections since it is detrimental to good work in the subsequent leveling operation. It is considered desirable for good results in leveling the toes of shoes that the leveling roll act on one side of the toe with its axis substantially inclined to the height of the shoe and then tip across the end of the sole and act similarly on the opposite side of the toe, in order properly to close the crease between the welt or the sole and the upper. If the shoe, however, is jacked so low as to avoid damage to the sole at the beginning and the end of the leveling operation, the shoe is too low to receive adequate leveling pressure from the roll as the latter operates on the toe, and with the shoe in such relation to the roll the pressure is frequently

not as great as would be desirable on other portions of the sole. On the other hand, if the machine is provided with a roll-receiver in the above-mentioned relation to the toe, this receiver is necessarily so close to the plane of the sole that the receiver, instead of the shoe, is likely to receive most of the pressure of the roll as the roll is tipped about the toe. Satisfactory results heretofore have therefore frequently required that the operator supplement the action of the machine by more or less hand work.

This invention affords a solution of the above-mentioned difficulties by the provision of means for controlling the relation between the leveling tool and the shoe in such manner as to avoid damage to the shoe without objectionably limiting the pressures applied in the leveling operation. The machine herein shown has means for relieving the leveling roll and its support or carrier of the force of its operating spring until after the toe end of the shoe is under the roll at the beginning of the leveling operation and when the toe passes out from under the roll at the end of the leveling operation, while rendering the spring effective at other times to apply the required leveling pressure. Still further to assist in accomplishing the objects in view, the invention provides means for supporting the leveling tool substantially out of contact with the shoe as the toe passes under it or out from under it in the relative movements of the tool and the shoe, so that there is no danger of damage to the shoe by reason of the weight of the tool and its carrier. While the machine herein shown thus comprises in its organization means for relieving the roll and its carrier of the force of its operating spring and means for supporting the roll substantially out of contact with the shoe at times, as above set forth, it will be recognized that in a substantial degree the purposes of the invention are served by either of these features, although for better insurance of satisfactory results it is considered generally preferable to combine them.

Considered in another aspect, the invention provides a means, preferably resilient, tending to support the leveling tool out of contact with the shoe at all times, and a pressure mechanism for overcoming or in-

hibiting the action of this means at desired points. In the described machine, this means is a spring just strong enough to support the leveling arm, and the main pressure 5 spring, which is much stronger, compresses the weaker spring when the leveling action is taking place.

In the construction herein shown as a preferred embodiment of the above-mentioned 10 features, the means for controlling the leveling tool in such manner as to avoid damage to the shoe is independent of the shoe support, so that there is nothing in the character 15 of the shoe support to interfere with the proper action of the tool in leveling the toe end of the sole. The invention thus provides an organization adapted to apply proper leveling pressures to the toes of shoes by the action of a leveling tool tipped 20 or inclined at the opposite sides of the toe and rocked about the end of the toe in such manner as to bend the margin of the sole as much as is necessary to produce a properly closed crease.

25 In another aspect, the invention provides for the automatic leveling of forepart edges by moving the center of the roll beyond the tip end of the toe so that the overhanging periphery of the roll will mold the toe end 30 of the sole as desired. Preferably the adjustment will be such that the slant of the overhanging periphery at such times will be approximately the same as the inclination 35 of the shoe engaging surface of the roll laterally of the shoe during the molding of the lateral edges of the forepart.

It has heretofore been impossible to level 40 a sole edge under a horizontal as distinguished from a tipped roll, as the roll tipping mechanism has made no provision for positioning the roll without some degree of tip on either side of the shoe when operating on the edge. The present invention provides 45 mechanism for such treatment of the shoe when desired.

These and other features of the invention, comprising, among others, novel means for varying the leveling pressure, and a novel gage to aid the operator in correctly jacking 50 the shoe, will be better understood from the following description of a preferred embodiment of the invention shown in the drawings in which,

55 Fig. 1 is a side elevation of the machine; Fig. 2 is a rear elevation;

Fig. 3 is a detail of the roll tipping mechanism;

Fig. 4, 5 and 6 are details showing the pressure mechanism;

60 Figs. 7, 7^a and 8 are details illustrating the passage of the roll around the toe; and

Fig. 9 is a detail of the pressure cam.

The main frame 10 of the machine has the leveling arms or roll carriers 12 pivoted by 65 trunnions in its upper rear portion as shown

at 14. These leveling arms are tubular and contain shafts 16 which at their forward ends carry the heads 18 in which the leveling rolls 20 are pivotally mounted. These shafts are rockable by the segments 22 (Figs. 2 70 and 3) mounted on them in substantial alignment with the trunnions 14, so that the vertical movement of the arms does not substantially interfere with the rocking mechanism, the segments being operated by racks 75 24 for the purpose of tipping the rolls as will be well understood. This tipping movement is accomplished by a main tipping cam mounted on the main shaft 25 upon the rear side of the disk 26 as seen in Fig. 1, which 80 operates through link and lever connections comprising a link 28 attached to a crank arm 30 on a shaft 32 carrying a slotted crank arm 34. In the slot in this crank arm is mounted for adjustable up and down movement a head 52 which carries the end of a link 36 the other end of which is attached to a rack 24. There are two racks 24 one for each leveling arm and they are connected by a pinion 38 (Fig. 3) so that their movements will be oppositely directed at all times. The adjustable end of the link 36 is universally jointed to and moved by the horizontal arm 40 of a bell-crank having a vertical arm 42 with a roller 44 which is 90 operated by any one of four wing cams 46 corresponding respectively to the traverses of the leveling roll over the inside and outside shank and forepart of the shoe, these cams being controlled from the front of the 95 machine by suitable adjusting mechanism and operated by a corresponding set of fly cams, not shown, on the main shaft 25. The structure thus far described for tilting the leveling rolls will be found described fully 100 in Letters Patent No. 889,287, issued June 2, 1908, on the application of E. E. Winkley, to which reference may be made. Its operation may be briefly described by saying that the main cam, through the mechanism 105 28—30—32, produces a standard tipping cycle, and the cams 46, through the mechanism 42—40—36, modify this tipping cycle according to the setting of the head 52 produced by their action.

110 A novel feature introduced by the present invention involves the construction of the crank arm 34. This arm extends outwardly on both sides of the shaft 32 upon which it is mounted and includes two transverse arms 48. Upon the ends of the arms 48 is mounted a slotted bar 50 in which is mounted the sliding head 52 which carries the end of the link 36. The slot in this bar also extends to both sides of the shaft 32 so that the amount of the roll tip during the operation of the given wing cam 46 may be reduced to zero or even reversed if desired, by moving the head 52 into line with the shaft 32, or beyond it. This enables the operator to 115 120 125 130

level an outside shank for example, without any roll tip, which is desirable in the case of certain styles of shoes, and has not heretofore been possible with an automatic leveling machine.

5 The shoe 54 is held on a jack comprising a heel post 56 and a toe post 58 pivoted together at 60 to permit adjustment to 10 accommodate different lengths of shoes and 15 mounted on a shaft 62 which is rocked by a link and lever mechanism operated by a main cam 64 and a pair of auxiliary cams 66. The jack (of which there are two) and 20 its operating mechanism will be found fully 25 described in Letters Patent Nos. 1,011,301, issued Dec. 12, 1911 on the application of E. E. Winkley, and 1,239,664, issued Sept. 11, 1917 on the application of W. C. Baxter, and need not be further described here.

20 The leveling rolls are resiliently forced down upon the shoe by the pressure of springs 68 mounted in vertical channels in the main frame. These springs press at their bottom ends upon levers 70 pivoted at 25 their rear ends on the main frame at 72 and at their front ends to vertically extending links 74 which are pivoted to the leveling arms 12. The upper ends of the springs are engaged by plungers 76 engaging screws 30 78 extending upwardly in tapped sleeves 80, provided with lugs 82 with which arms 84 on a rock-shaft 86, which is mounted on the frame, are in engagement. The turning of the screws 78 by handles 88 alters the 35 distance between the lugs 82 and the plungers 76 for any given position of the arms 84 and thus exerts more or less pressure on the leveling arms, for any given condition of the mechanism.

40 The rock-shaft 86 is operated by a link 90 (Fig. 1) pivoted to an arm 91 on the shaft and to the end of a lever 92 upon which is 45 adjustably mounted the end of a link 94 having a roll 96 contacting with a cam 98 mounted on the main shaft 25. The lower 50 end of the link 94 has a slotted bearing on the main shaft to hold it in position. The high points upon the cam 98 raise the link 94 and exert pressure through the springs 55 68 upon the leveling arms and the low places on the cam are designed to relieve this pressure to a desired extent on certain parts of the shoe or to remove it entirely as may be desired. The cam 98 revolves once during 60 a leveling cycle and its high and low points determine the pressures applied at different points on the shoe and at different times during this cycle. Specifically, in the machine shown the depression 98^a relieves the 65 pressure of the spring 68 entirely at the beginning and end of the cycle, when the roll is going on or coming off the toe of the shoe. The high portion 98^b corresponds to the travel of the roll down the middle of

the forepart; the depression 98^c to a relief 65 of the pressure at the ball line as the roll passes to the shank; the portion 98^d to the reciprocation up and down the shank on one side; 98^e to a relief of pressure as the roll goes back over the ball; 98^f to the traverse over the same side of the forepart and back to the ball on the other side; 98^g to another relief as the roll goes back over the ball to the shank on the other side; 98^h to the reciprocation of the roll over the shank 75 on that side; 98ⁱ to a relief in going back over the ball; and 98^j to the return over the middle of the forepart to the toe.

Our invention provides, in accordance with one feature, for the elimination of pressure relief incidents of the leveling cycle at will, by means of the plugs 98^k held in position in the depressions by bolts 98^l (Fig. 9). It is unnecessary in the case of many shoes not having high arched shanks to relieve 85 the pressure in passing over the ball, and in some cases such relief may be positively undesirable. The removable plug feature thus provides for the relief of pressure or not, at the will of the operator.

90 The leveling arm 12 near its front end rests upon a vertical plunger 102 (Fig. 5) which is supported by a spring 104 the pressure of which can be adjusted by a screw device 106. This plunger is supported in a 95 barrel 108 mounted upon the main frame of the machine and the spring 104 is a trifle stronger than is necessary to sustain the weight of the leveling arm and roll. The plunger has sufficient amplitude of 100 movement in its barrel to permit the entire range of vertical movement of the leveling arm which may be found desirable, so that when the comparatively powerful spring 68 105 comes into action the spring 104 and plunger 102 do not perceptibly interfere in any way with the movements of the arm 12 under the pressures exerted by the spring 68 and the shoe 54.

110 This auxiliary spring 104 and the relief feature of the cam 98 already alluded to are very important elements in the accomplishment of the objects of the invention. A great deal of difficulty has heretofore been experienced in leveling properly the toes of 115 some types of shoes because, if the roll came on the toe under pressure at the beginning of the leveling operation, it was very liable to "stub" the toe, by which is meant to strike it longitudinally, and to bruise or deform it. In order to avoid this difficulty it has been the custom to set the shoe so low in its jack that little or no pressure was exerted by the roll as it went on to the shoe (the spring 68 being comparatively lightly stressed when the roll is low), and with the shoe positioned in this relation to the roll 120 adequate leveling pressure was never exerted

on the toe, and in some cases not on other portions. Further, as already suggested, if the jack was provided with a roll receiver to guide the roll, the roll would tip around the toe with more or less pressure on the receiver instead of on the shoe, so that the toe would not be treated at all or very inadequately. The action of the roll in going around the toe properly, as provided by the present invention, is illustrated in Figs. 7 and 8. Fig. 7 shows the relation of the center of the roll to the tip end of the sole at the middle of its passage around the toe. It will be noticed that the center of the roll is a little ahead of the end of the sole so that an upwardly sloping portion of the periphery of the roll is in contact with the edge of the sole. Fig. 8, which is a view taken in the direction of the arrow in Fig. 1, illustrates the tipping of the roll around the end of the toe. It will be seen that there is nothing about the toe to interfere with the tipping of the roll. The present invention, as already explained, in its illustrated embodiment provides that the pressure due to the main spring 68 is relieved entirely as the roll goes on to the toe, but this condition is only temporary and lasts only until the roll has gone on to the shoe. The auxiliary spring 104 lifts the leveling arm and roll to their limiting upward position when the main spring pressure is removed and thus enables the roll to pass on to the toe under no pressure whatever without any low-jacking of the shoe and consequent diminishing of the effective pressure of the roll in the remainder of the leveling operation. Indeed, the parts and shoe can be so adjusted that the roll is spaced a substantial distance above the toe end of the sole as it passes over it at the beginning, and so that, as the pressure goes on, it will initially strike an actual blow on the sole at the toe, thus simulating the effect of the hand hammer which has always had to be used at this point on many shoes. It should be noticed that the disclosed machine has no roll receiver in front of the toe, this member being quite unnecessary where the present invention is used.

The shoe will preferably be jacked so that its toe is in such relation to the center of the roll, as the roll acts on the end of the sole, that the tangent to the roll periphery lying in a vertical plane containing the long axis of the sole at the point of contact of the roll periphery and the sole will have about the same inclination to the horizontal as that of the shoe engaging surface of the roll as the roll treats the side edges of the fore-part. Thus the overbending of the sole edge is secured at the sides of the sole by the roll tip and is secured at the end by the overhanging circular periphery of the roll.

Fig. 7^a shows a more extreme condition than Fig. 7, secured by jacking the shoe a little farther back.

The leveling roll 20 itself is mounted in a carriage or head 110 having arc or segmental shaped lateral extremities at 112 whereby it may be rotated about a vertical axis in the head 18 and held in adjustable position by a screw and slot arrangement at 114. This enables the roll to be adjusted to suit certain kinds and conditions of work. The roll may be adjusted, for example, so that its axis extends substantially in the same direction as the ball line of the shoe and is substantially parallel to the heel breast line as the roll operates at the shank of the shoe, such adjustment of the roll being maintained throughout the leveling operation, so that the roll in operating at the toe has its axis more nearly parallel to the edge line of the sole at the outer side of the toe than to the edge line at the inner side. A pad 116 rests upon the top of the roll to wipe off dirt. A gage 118 is mounted in the head 110 to extend outwardly over the front of the roll and serve as a guide for the jacking of the toe end of the shoe so that it may be properly placed horizontally and vertically prior to the beginning of the leveling operation.

The toe post 58 has at its upper end a socket 120 arranged to hold a rubber toe pad 122, which is the sole invention of Herman Davenport, and is described and claimed in Letters Patent No. 1,602,393, granted on October 12, 1926.

Having described our invention, what we claim as new and desire to secure by Letters Patent of the United States is:—

1. In a leveling machine, a shoe support, a leveling tool, means for automatically producing relative traverses of the leveling tool and a shoe on the support, mechanical means for exerting pressure on the shoe through the tool, and means constructed and arranged substantially to relieve the pressure due to said means as the tool passes on to the shoe at the beginning of the operation.

2. In a leveling machine, a shoe support, a leveling tool, means for relatively moving the support and tool to cause the tool to cross the sole edge of a shoe on the support at the beginning of the leveling operation, means for exerting pressure between the shoe and tool during the leveling operation, and means for holding the tool out of contact with the sole edge as it passes across it at the beginning of the leveling operation.

3. In a leveling machine, a shoe support, a leveling tool, means for relatively moving the support and tool to cause the tool to cross the sole edge of a shoe on the support at the beginning of the leveling operation, and a resilient device for supporting the tool out

of contact with the shoe at the time described.

4. In a leveling machine, a shoe support, a leveling tool, means for relatively moving the support and tool to cause the tool to cross the sole edge of a shoe on the support at the beginning of the leveling operation, a continuously acting device for supporting the tool out of contact with the shoe, a pressure device tending to force the tool into contact with the shoe, and means for causing the effect of the first said device to predominate at the beginning of the leveling operation.

5. In a leveling machine, a shoe support, a leveling tool, means for relatively moving the support and tool to cause the tool to cross the sole edge of a shoe on the support at the beginning of the leveling operation, a continuously acting device for supporting the tool out of contact with the shoe, a pressure device tending to force the tool into contact with the shoe and arranged normally to predominate in effect over the first said device, and means for reversing this condition of predominance as the tool passes across the sole edge at the beginning of the leveling operation.

6. In a leveling machine, a shoe support, a leveling tool, means for relatively moving the support and tool to cause the tool to cross the sole edge of a shoe on the support at the beginning of the leveling operation, a resilient member arranged to support the tool so that substantially no pressure will be impressed on the sole edge at the instant of crossing it, a pressure mechanism for normally effecting pressure between the tool and the shoe, and cam operated means for rendering the pressure mechanism inoperative at the said instant of crossing.

7. In a leveling machine, a shoe support, a leveling arm pivoted for vertical movement substantially perpendicular to the sole of a shoe on the support, a resilient device arranged to support said arm so as to hold a tool carried thereby at or above the level of the sole edge of a shoe on the support, means for effecting relative movement of the arm and the shoe, a pressure device arranged to exert pressure on the arm to force it toward the shoe and normally to operate said arm irrespective of the stress exerted by the resilient device, and a cam and connections for controlling the pressure device arranged to render it ineffective as regards opposition to the resilient device at the instant of the crossing of the sole edge by the tool.

8. In a leveling machine, a shoe support, a leveling arm pivoted for vertical movement substantially perpendicular to the sole of a shoe on the support, a resilient device arranged to carry substantially the entire weight of the arm and to hold it up out of pressing relation to the shoe at the instant

of the crossing of the sole edge by a tool on the leveling arm, a spring for forcing the leveling arm down toward the shoe and substantially stronger than the resilient device so that the latter is ineffective to hold the arm up when the spring is in operation, and a cam and connections for putting the spring out of action at the said instant of crossing.

9. In a leveling machine, a leveling arm mounted on a horizontal pivot to move vertically, a jack on a horizontal pivot, arranged to carry a shoe back and forth under a roll mounted on the arm, a spring connected with the arm arranged to support it at the upper limit of its vertical path, a second and much stronger spring arranged to force the leveling arm downward toward the shoe, and means for relieving the pressure of the stronger spring at the instant the tool crosses the sole edge of the shoe.

10. In a leveling machine, a shoe support, a leveling roll, means for effecting relative traverse between the roll and a shoe on the support, means for tipping the roll about an axis generally parallel to the length of the shoe, comprising a main roll tipping cam, and an auxiliary controlling mechanism arranged to counteract completely the action of the said main tipping cam on selected portions of the shoe.

11. In a leveling machine, a shoe support, a leveling roll, means for effecting relative traverse between the roll and a shoe on the support, and means for tipping the roll about an axis generally parallel to the length of the shoe, comprising a main roll tipping cam, a lever connected therewith, and a head adjustable along the lever and connected to the leveling roll, said head and lever being constructed to permit the positioning of the head at the pivot of the lever, if desired, to counteract the action of the main tipping cam.

12. In a leveling machine, a shoe support, a leveling roll, means for effecting relative traverse between the roll and a shoe on the support, means for tipping the roll about an axis generally parallel to the length of the shoe, comprising a main roll tipping cam, a lever connected therewith, and a head adjustable along the lever and connected to the leveling roll, said head and lever being constructed to permit the positioning of the head, in line with the pivot of the lever if desired, and automatic means for effecting the positioning of the head during the operation of leveling a shoe.

13. In a leveling machine, a shoe support, a leveling roll, means for effecting relative traverse between the roll and a shoe on the support, means for tipping the roll about an axis generally parallel to the length of the shoe, comprising a main roll tipping cam, a lever connected therewith, and a head adjustable along the lever and connected to

the leveling roll, said head and lever being constructed to permit the positioning of the head in line with the pivot of the lever if desired, and adjustable means for automatically effecting the positioning of the head during the operation of leveling a shoe.

14. In a machine of the class described, a shoe holding jack, a leveling arm, a tool on the arm, and a gage in operative relation to the leveling tool and jack to determine their relative adjustment prior to the beginning of the leveling operation.

15. In a machine of the class described, a shoe holding jack, a leveling arm, a tool on the arm, and a gage mounted on the arm in operative relation to the jack to determine the relative adjustment of the shoe and tool prior to the beginning of the leveling operation.

16. In a machine of the class described, a shoe holding jack, a leveling arm, a tool on the arm, and a gage adjustably mounted on the arm in front of the tool to determine the height to which the shoe is to be set prior to the beginning of the leveling operation.

17. In a leveling machine, a shoe support, a leveling tool, means for automatically producing relative traverses of the leveling tool and a shoe on the support, means for tipping the tool around the toe of the shoe as it passes from one side of the forepart to the other, mechanical means for exerting pressure on the shoe through the tool, and means constructed and arranged substantially to relieve the pressure due to said means as the tool passes on to the shoe at the beginning of the operation.

18. In a leveling machine, a shoe support, a leveling tool, means for relatively moving the support and tool to cause the tool to cross the sole edge of a shoe on the support at the beginning of the leveling operation, means for exerting pressure between the shoe and tool during the leveling operation, means for carrying the tool around on the end of the toe during the leveling operation, and means for holding the tool out of contact with the sole edge as it passes across it at the beginning of the leveling operation.

19. In a leveling machine, a shoe support, a leveling tool, means for relatively moving the support and tool to cause the tool to cross the sole edge of a shoe on the support at the beginning of the leveling operation, means for traversing and tipping the tool around on the end of the toe of the shoe, and a resilient device for supporting the tool out of contact with the shoe at the said beginning of the operation.

20. In a leveling machine, a shoe support, a leveling tool, means for relatively moving the support and tool to cause the tool to cross the sole edge of a shoe on the support at the beginning of the leveling operation,

means for exerting pressure between the shoe and tool during the leveling operation, means for holding the tool out of contact with the sole edge as it passes across it at the beginning of the leveling operation, and means for abruptly establishing pressure between the tool and the sole immediately after said passage.

21. In a leveling machine, a shoe support, a leveling arm pivoted for vertical movement substantially perpendicular to the sole of a shoe on the support, a resilient device arranged to carry substantially the entire weight of the arm and to hold it up out of pressing relation to the shoe at the instant of the crossing of the sole edge by a tool on the leveling arm, a spring for forcing the leveling arm down toward the shoe and substantially stronger than the resilient device so that the latter is ineffective to hold the arm up when the spring is in operation, and a cam and connections for putting the spring out of action at the said instant of crossing, and for abruptly restoring the action of the spring immediately after the said instant of crossing.

22. In a leveling machine, a shoe support, a leveling tool, means for relatively moving the support and tool to cause the tool to cross the sole edge of a shoe on the support at the beginning of the leveling operation, a device for supporting the tool out of contact with the shoe at the time described, a pressure device tending to force the tool into contact with the shoe and arranged normally to predominate in effect over the first said device, means for reversing this condition of predominance as the tool passes across the sole edge at the time described, and means for abruptly restoring the said condition immediately after the said passage.

23. In a machine of the class described, a shoe support and a roll and means automatically to effect relative traverse of a shoe on the support and the roll in such manner that the center of the roll passes beyond the toe tip as the toe tip is being leveled, to bend the sole at the toe tip by the overhanging periphery of the roll.

24. In a machine of the class described, a shoe support and a roll and means automatically to effect relative traverse of a shoe on the support and the roll and to tip them relatively during the traverse, the shoe support, roll and traversing means being organized to carry the center of the roll beyond the tip of the toe, as the toe is being leveled, to such an extent that the toe tip of the sole is bent by the overhanging roll periphery to substantially the same extent that the lateral edges of the forepart are bent by the relative tipping of the shoe and roll.

25. In a machine of the class described, a shoe support, a roll, and means automatic-

- cally to effect relative traverse of a shoe on the support and the roll, all constructed and arranged to move the center of the roll beyond the toe tip to a predetermined extent, and means for tipping the roll, whereby the toe tip is molded by relatively tipping the roll across the toe tip while its center is beyond the toe tip.
26. In a machine of the class described, a shoe support, a leveling tool, means for effecting relative traverse of the tool and a shoe on the support, a pressure mechanism for effecting pressure between the tool and the shoe, comprising means for approximately removing all pressure exerted by the mechanism at predetermined points, and means for inhibiting the action of the pressure removing means at the will of the operator.
27. In a machine of the class described, a shoe support, a leveling tool, means for effecting relative traverse of the tool and a shoe on the support, a pressure mechanism for effecting pressure between the tool and the shoe, comprising means for varying the pressure from point to point on the shoe, and means for inhibiting selected pressure-variation incidents at will.
28. In a machine of the class described, a shoe support, a leveling tool, means for effecting relative traverse of the tool and a shoe on the support, a pressure mechanism for effecting pressure between the tool and the shoe comprising a cam, and means for locally varying the shape of the cam.
29. In a machine of the class described, a shoe support, a leveling tool, means for effecting relative traverse of the tool and a shoe on the support, and a pressure mechanism for effecting pressure between the tool and the shoe comprising a cam arranged for the insertion of one or more auxiliary pieces for the purpose of effecting local alterations in its contour.
30. In a machine of the class described, a shoe support, a leveling tool, means for effecting relative traverse of the tool and a shoe on the support, a pressure mechanism for effecting pressure between the tool and the shoe comprising a cam, and detachable cam members for the cam whereby its configuration may be locally altered.
31. In a machine of the class described, a shoe support, a leveling tool, means for effecting relative traverse of the tool and a shoe on the support, a pressure mechanism for effecting pressure between the tool and the shoe comprising a cam having notches corresponding to incidents of the pressure cycle, and a plug arranged to fill a notch to inhibit the corresponding pressure incident.
32. In a leveling machine, the combination with a shoe support and a leveling tool relatively movable to position the tool over the bottom of a shoe and then to cause the tool to operate along the shoe bottom, of automatic means tending to determine a relation between the shoe and the tool such as to prevent substantial pressure of the tool on the shoe at all times, and pressure means for overcoming the automatic means at desired points.
33. In a leveling machine, the combination with a shoe support and a leveling tool relatively movable lengthwise of a shoe to position the tool over the toe end of the shoe bottom and then to cause the tool to operate along the shoe bottom, of automatic means independent of the shoe support for positioning the tool in such relation to the shoe as to prevent substantial pressure of the tool on the shoe until after the tool is over the edge of the toe end of the shoe bottom.
34. In a leveling machine, the combination with a leveling tool, of a shoe support constructed to leave the end and the sides of the toe of a shoe free to permit the tipping of the tool about the toe for leveling the edge of the sole, means for effecting relative movement of the shoe support and the tool lengthwise of the shoe to position the tool over the toe end of the sole and then to cause the tool to operate along the sole, and means for positioning the tool in such relation to the shoe as to prevent substantial pressure of the tool on the shoe until after the tool is over the edge of the sole and for then bringing the pressure of the tool to bear upon the sole.
35. In a leveling machine, the combination with a shoe support and a leveling tool relatively movable lengthwise of a shoe to position the tool over the toe end of the sole and then to cause the tool to operate along the sole, of spring means for pressing the tool forcibly upon the sole, and mechanism operative in time relation to the relative movement of the tool and the shoe lengthwise of the shoe to relax the force of said spring means until after the tool is over the edge of the sole and then substantially to increase the force of said spring means.
36. In a leveling machine, the combination with a shoe support and a leveling tool relatively movable lengthwise of a shoe to position the tool over the toe end of the shoe bottom and thereafter to cause the tool to operate along the shoe bottom and then to restore the parts to starting position, of spring means for pressing the tool forcibly upon the shoe bottom, and automatic mechanism for relaxing the force of said spring means when the tool crosses the edge of the toe end of the shoe bottom both at the beginning and at the end of the leveling operation.
37. In a leveling machine, the combination with a shoe support and a leveling tool

- 8
- relatively movable lengthwise of a shoe to level the shoe bottom and finally to cause the tool to cross the edge of the shoe bottom in the return of the parts to starting position, of spring means for pressing the tool forcibly upon the shoe bottom, and automatic mechanism for relaxing the force of said spring means when the tool crosses said edge to prevent damage to the shoe.
- 10 38. In a leveling machine, the combination with a shoe support and a leveling tool relatively movable lengthwise of a shoe to level the sole thereof, of automatic means independent of the shoe support tending to support the tool out of contact with the shoe at all times, and pressure means for nevertheless bringing the tool into operative pressing relation to the shoe wherever desired.
- 15 39. In a leveling machine, the combination with a shoe support and a leveling tool relatively movable lengthwise of a shoe to position the tool over the toe end of the shoe bottom and then to cause the tool to operate along the shoe bottom, of constantly acting resilient means for supporting the tool in a position higher than it occupies in leveling the toe end of the shoe bottom, and means for forcing the tool downwardly against the resistance of said resilient means to apply leveling pressure only after the tool is positioned over the toe end of the shoe bottom.
- 20 40. In a leveling machine, the combination with a shoe support and a leveling tool relatively movable lengthwise of a shoe to level the shoe bottom and finally to cause
- the tool to cross the edge of the shoe bottom in the return of the parts to starting position, of automatic means for positioning the shoe and the tool in such relation as to prevent substantial pressure of the tool on the shoe as the tool crosses said edge without substantially affecting the subsequent leveling pressure applied to the shoe.
- 25 41. In a leveling machine, the combination with a shoe support and a leveling tool relatively movable lengthwise of a shoe, of mechanism for effecting relative tipping movement of the shoe and the tool to incline the tool relatively to the bottom face of the sole in operating on the side edges of the sole, said mechanism being so constructed as to permit relative positioning of the shoe and the tool with the tool substantially parallel to the bottom face of the sole in operating on the side edges of the sole.
- 30 42. In a leveling machine, the combination with a shoe support and a leveling roll relatively movable lengthwise of a shoe, of automatic roll tipping mechanism for positioning the roll with its axis inclined relatively to the bottom face of the sole in operating on the side edges of the sole, said roll tipping mechanism being so constructed as to permit the roll to be positioned with its axis substantially parallel to the bottom face of the sole in operating on the side edges of the sole.

In testimony whereof we have signed our names to this specification.

ERASTUS EDWIN WINKLEY.

HERMAN AUGUSTUS DAVENPORT.
